11 Claims. (Cl. 260—293.4)

The present invention concerns di-alkyl-piperidyl-methanols of the formula

in which Pi represents a piperidyl radical, R₁ and R₂ alkyl radicals containing from 4 to 16 carbon atoms, and their acid addition salts and quaternary ammonium salts. R₁ and R₂ may be different but they are preferably identical.

The piperidyl radical, which is connected with the radical of the molecule in positions 2, 3 or 4 and preferably in position 3 or 4, may be substituted by lower alkyl groups in any position, for instance methyl, ethyl, propyl, butyl; especially it is substituted at the nitrogen atom by lower alkyl or hydroxyalkyl groups. Suitable substituents at the nitrogen are for instance methyl, ethyl or propyl, hydroxyethyl or hydroxypropyl.

For the present purpose quaternary ammonium salts are above all lower alkyl-ammonium salts, the anion being selected from the group consisting of mineral acids, for instance hydrohalic acids, such as hydrochloric acid, hydrobromic acid or hydroiodic acid, or sulfuric acid or of organic sulfonic acids, for instance lower alkyl sulfonic acids such as methane or ethane sulfonic acid or aryl sulfonic acids, such as benzene sulfonic acid, p-toluene sulfonic acid, p-bromobenzene sulfonic acid.

The new compounds possess valuable properties. Inter alia they have fungicidal and especially antibacterial properties, for example against *Microsporum audouini*, *Trichophyton interdigitalis* and *Staphylococcus aureus* and they act against tubercle bacilli and can therefore be used as disinfectants, preservatives or medicaments for the treatment of bacterial infections, for example such as have been caused by the abovementioned organisms.

Of special value in this respect are the compounds of the formula

as well as their therapeutically useful acid addition salts and quaternary lower alkyl-ammonium salts which are distinguished also by their stability towards soap and sera. Special mention deserve di-octyl-3-piperidylmethanol, di-octyl-4-piperidylmethanol, di-decyl-3-piperidylmethanol, di-hexyl-3-piperidylmethanol, di-hexyl-4-piperidylmethanol, their acid addition salts and quaternary ammonium salts.

The new compounds are obtained by methods as such known. Thus an alkyl pyridine of the formula

2

in which R₁ and R₂ have the above meaning and Py represents an unsubstituted or lower alkyl substituted pyridyl radical, can be treated with a hydrogenating agent.

The hydrogenation can be carried out with an agent known to be suitable for hydrogenating a pyridine ring. Thus, for example, the hydrogenation is carried out with hydrogen in the presence of a catalyst of a metal of the eighth group of the Periodic System, preferably a noble metal catalyst such as platinum or palladium, for example with platinum in glacial acetic acid or palladium carbon in alcohol or isopropanol, or in the presence of cobalt or nickel (Raney or Rupe).

A secondary alkyl-piperidine compound obtained by the present process can be converted into a tertiary compound in the known manner. It can, for example, by alkylated in the usual manner or converted into the corresponding tertiary hydroxyalkyl derivative, for example, by treatment with a 1:2-alkylene oxide.

A tertiary amino compound obtained by the present process can be quaternated in the conventional manner, preferably with a reactive ester of a lower alkanol, such as an ester thereof with a mineral acid or an organic sulfonic acid as mentioned above, for example a hydrohalic acid, sulfuric acid or an arylsulfonic acid.

Depending on the procedure used the new compounds are obtained in the form of their bases or salts. From the salts the free bases can be prepared in the known manner. Reaction of a free base with an acid suitable for the preparation of therapeutically useful salts yields salts, for example those of the hydrohalic acids, e.g., hydrochloric or hydrobromic acid, perchloric acid, nitric or thiocyanic acid, or sulfuric acid, or phosphoric acid, or organic acids, such as formic acid, acetic acid, propionic acid, glycolic acid, lactic acid, pyruvic acid, oxalic acid, malonic acid, succinic acid, maleic acid, fumaric acid, malic acid, tartaric acid, citric acid, ascorbic acid, hydroxy maleic acid, dihydroxymaleic acid, benzoic acid, phenylacetic acid, 4-aminobenzoic acid, 4-hydroxybenzoic acid, anthranilic acid, cinnamic acid, mandelic acid, salicylic acid, 4-aminosalicylic acid, 2-phenoxybenzoic acid, 2-acetoxybenzoic acid, methanesulfonic acid, ethanesulfonic acid, hydroxyethanesulfonic acid, benzene- or p-toluenesulfonic acid, naphthalenesulfonic acid, or sulfanilic acid.

The new compounds may contain asymmetrical carbon atoms so that they are obtained in the form of racemate mixtures. Such mixtures can be separated by a usual method, such as crystallization. The individual racemates can be resolved into their optically active antipodes by the conventional method.

50 The starting materials are known or can be made by as such known methods.

The new compounds can be used in human or veterinary medicine as medicaments in the form of pharmaceutical preparations containing them in admixture with a suitable vehicle or diluent. Suitable vehicles are, for example, substances that do not react with the new compounds, such as water, gelatine, lactose, starch, magnesium stearate, talc, vegetable oils, benzyl alcohols, gums, polyalylene glycols, white petroleum jelly, cholesterol or other known medicinal vehicles. The pharmaceutical preparations may be, for example, tablets, dragees, powders, ointments, creams, suppositories or in liquid form solutions, suspensions or emulsions. They may be sterilized and/or may contain assistants such as preservatives, stabilizers, wetting agents or emulsifiers. They may further contain other therapeutically valuable substances.

The new compounds are also suitable as disinfectants

or preservatives, for example for disinfecting the skin, for example the hands, instruments, underwear or the like, and also for disinfecting or preserving victuals or feeding-stuffs. They may be applied by themselves or in admixture in a solution or emulsion and/or with other active principles or inert substances, such as ointments, or in the form of dry powders.

The following examples illustrate the invention without restricting its scope thereto.

Example 1

A solution of 98 grams of di-lauryl-3-pyridylmethanol in 400 cc. of isopropanol is hydrogenated with the aid of 5 grams of palladium carbon of 10% strength as catalyst in an autoclave with hydrogen at 115° C. under a pressure of 100 atmospheres gauge until the pressure remains constant. The catalyst is then filtered off, the solvent is evaporated and the residue (95 grams) is distilled in a high vacuum.

Di-lauryl-3-pyridylmethanol boils at 231-240° C. under a pressure of 0.12 mm. Hg or at 130-135° C. under a pressure of 11.5 microns (molecular distillation apparatus). It corresponds to the formula

When the product is dissolved in methanol, treated with a calculated amount of hydrochloric or acetic acid and evaporated, the hydrochloride (M.P.=84-86° C.) and the acetate respectively is obtained.

The aforementioned starting material is prepared by adding a solution of 30.2 grams of nicotinic acid ethyl ester in 250 cc. of toluene dropwise at 30-50° C. to an ethereal solution of the Grignard compound prepared from 12.15 grams of magnesium and 131 grams of lauryl bromide and stirring the mixture for 4 hours at 60° C. under nitrogen. The Grignard complex is decomposed in a solution of ammonium chloride which is then worked up in the usual manner, the whole is distilled in a high vacuum and the forerunnings are separated, whereupon di-lauryl-3-pyridylmethanol is obtained.

Instead of nicotinic acid ethyl ester it is possible to use nicotinic acid methyl ester which boils at 235-237° C. under 0.05 mm. Hg pressure.

Example 2

A solution of 19.4 grams of di-lauryl-4-pyridylmethanol in 100 cc. of methanol and 5 cc. of acetic acid is hydrogenated with the aid of 1.5 grams of platinum oxide as catalyst with hydrogen under atmospheric pressure at 25° C. The catalyst is filtered off, the solvent evaporated, the residue is rendered alkaline (pH=11) with sodium hydroxide solution, the precipitated oil is extracted with ether, the ether solution is washed until neutral and then dried and the ether is distilled off. The residue is then distilled in a high vacuum to yield 16 grams of di-lauryl-4-pyridylmethanol of the formula

passing over at 229-231° under a pressure of 0.07 mm. Hg.

The aforementioned starting material is prepared as described in Example 1 with the use of isonicotinic acid methyl or ethyl ester. It boils at 220-225° C. under a pressure of 0.07 mm. Hg and melts at 80-81° C.

Example 3

The following compounds are prepared as described in Examples 1 and 2:

		Boiling at °C.	Under mm. Hg	Melting at °C.
5	Di-butyl-3-piperidylmethanol	143-150	0.1	96-97
10	Di-hexyl-3-piperidylmethanol	136-141	0.07	-----
	Di-hexyl-3-(1-methylpiperidyl)-methanol	175-180	0.1	-----
	Di-octyl-3-piperidylmethanol	207-211	0.09	-----
	Di-hexadecyl-3-piperidylmethanol	285-290	0.09	-----
15	Di-butyl-4-piperidylmethanol	122-126	0.07	-----
	Di-butyl-4-piperidylmethanol	148-150	0.07	-----
	Di-octyl-4-piperidylmethanol	185-187	0.09	-----
	Di-decyl-4-piperidylmethanol	209-211	0.11	78-79
	Di-hexadecyl-4-piperidylmethanol			

The starting materials to be used are prepared as described in Example 1:

		Boiling at °C.	Under mm. Hg	Melting at °C.
20	Di-butyl-3-pyridylmethanol	128-131	0.08	-----
25	Di-hexyl-3-pyridylmethanol	140-150	0.08	-----
	Di-octyl-3-pyridylmethanol	188-191	0.06	-----
	Di-decyl-3-pyridylmethanol	221-223	0.1	-----
	Di-hexadecyl-3-pyridylmethanol	290-305	0.06	-----
30	Di-butyl-4-pyridylmethanol	128-131	0.09	-----
	Di-octyl-4-pyridylmethanol			61-62
	Di-decyl-4-pyridylmethanol	178-184	0.06	67-68
	Di-hexadecyl-4-pyridylmethanol	220-225	0.07	-----
		275-285	0.07	89-90

Example 4

When a mixture of a solution of 8 grams of di-lauryl-3-pyridylmethanol in 60 cc. of ethyl acetate and 2.7 grams (=2 cc.) of dimethyl sulfate is left to itself for one hour, then evaporated to dryness, the di-lauryl-3-pyridylmethanol-methosulfate formed is dissolved in 50 cc. of methanol and the solution is hydrogenated with 0.5 gram of platinum oxide under hydrogen at 25° C. under atmospheric pressure, di-lauryl-3-(1-methyl-piperidyl)-methanol of the formula

45

50 is obtained which boils at 230-232° C. under a pressure of 0.09 mm. Hg.

Example 5

A mixture of 6 grams of di-lauryl-3-(1-methyl-piperidyl)-methanol (prepared as described in Example 4) dissolved in 15 cc. of ethyl acetate and 3 cc. of methyl iodide is left to itself for 3 hours and then heated for 10 minutes at 60° C., whereupon the methiodide of di-lauryl-3-(1-methyl-piperidyl)-methanol of the formula

60

crystallizes out; it melts at 85-86° C.

70

Example 6

2 grams of ethylene oxide are added to a solution of 10 grams of di-lauryl-3-piperidyl-methanol in 50 cc. of methanol. The additive reaction is catalyzed by adding 1 cc. of N-acetic acid. The reaction mixture is kept overnight, evaporated to dryness and the residue is dis-

75

tilled in a high vacuum, to yield di-lauryl-3-(1- β -hydroxyethyl-piperidyl)-methanol of the formula

6. The compound di-decyl-3-piperidyl-methanol.
7. A therapeutically useful acid addition salt of the compound of claim 2.
8. A therapeutically useful acid addition salt of the compound of claim 3.
9. A therapeutically useful acid addition salt of the compound of claim 4.
10. A therapeutically useful acid addition salt of the compound of claim 5.
11. A therapeutically useful acid addition salt of the compound of claim 6.

What is claimed is:

1. A member selected from the group consisting of a compound of the formula

wherein R stands for a member selected from the group consisting of hydrogen, lower alkyl and hydroxyalkyl and each of the letters n and m stands for one of the integers from 5 to 11, inclusive, and a therapeutically useful acid addition salt thereof and a quaternary lower alkyl ammonium salt thereof.

2. The compound di-octyl-3-piperidyl-methanol.
3. The compound di-octyl-4-piperidyl-methanol.
4. The compound di-hexyl-3-piperidyl-methanol.
5. The compound di-hexyl-4-piperidyl-methanol.
